United States Patent Office.

HENRY BARTH, OF CINCINNATI, OHIO.

Letters Patent No. 99,133, dated January 25, 1870.

IMPROVEMENT IN SHEET-GAUGES FOR PRINTING-PRESSES.

The Schedule referred to in these Letters Patent and making part of the same

I, HENRY BARTH, of Cincinnati, in the county of Hamilton, and State of Ohio, have invented a certain Improvement in Drop-Guides for Printing-Presses, of which the following is a specification.

My invention relates to an improvement in the drop-guides of printing-presses, which enables their ready and accurate adjustment.

General Description with Reference to the Drawings.

Figure 1 is a perspective view of my improved drop-guide, with portions of the contiguous parts of the press.

Figure 2 is a longitudinal section of the guide.

Figure 3 is a horizontal section through the pinion.

Figure 4 is a transverse section, at the line X X, (with the pinion removed.)

Figure 5 is a perspective view of the bracket.

Of the above, figs. 2 to 5, inclusive, are full size.

A is a portion of the frame, B of the feed-board, and C of the cylinder of a printing-press.

D is the drop-guide shaft, to which a rocking motion is imparted by usual, or any preferred means.

E is a collar or bracket, which admits of adjustment on said shaft, and which is held to the proper position by a set-screw, F, which has a milled head, f, and a screw-threaded portion, f', adjoining thereto, and upon which plays a milled jamb-nut, G.

Between the screw-threaded portions f' and f'', the latter of which turns in a screw-hole of the bracket, is a cylindrical portion, f'', which serves as the arbor of a cog-pinion, H, having a milled head or disk, h, by which it is turned.

I is the guide proper, which has the customary down-turned portion i, to receive the impingement of the advancing edge of the sheet of paper. This portion i, when in action, rests upon a metallic tongue, extending from the lower edge of the feed-board, and is, when the fingers or grippers are about to "take" the sheet, raised up in the usual manner by the rock of the guide-shaft D, to allow the sheet to pass beneath it.

K is a longitudinal slot in the guide-plate I, which receives a raised portion, L, of the bracket; and the said raised portion has a circular cavity, l, to receive the pinion H, the said cavity being open at one side,

to allow the teeth of the pinion to engage those of a rack, k, upon one side of the slot K in the guide-plate. k' is a flange upon the head of the pinion, which rests upon the top of the guide I.

Operation.

When in use, the bracket E is firmly fixed to the shaft D, by means of the set-screw F, and the guide held in place upon the bracket by the flange k', which is pressed down by the jamb-nut G, that also assists to tighten the set-screw.

When it is desired to adjust the guide upon the bracket, the jamb-nut is turned, so as to raise it from the pinion-head, and the pinion may then be freely turned, and operates, through the rack k, to give the required adjustment to the guide, the raised portion L serving to keep the guide straight with the bracket.

I have described only those parts which are embraced in my improvement, namely, the bracket and guide, with the adjusting and setting-mechanism; the rock-shaft, and the remainder of the printing-press, having the usual, or any suitable construction.

Claims.

I claim, as my invention—

1. The combination, with the guide-plate I, of the rack k, pinion H, screw F f', and jamb-nut G, for adjusting said guide-plate, as herein represented and described.

2. In combination with the guide-plate I, adjustable by means of rack and pinion k H, clamp-screw F f', and jamb-nut G, as described, the longitudinal slot K, and guide I, as and for the purpose set forth.

3. In combination with an adjustable bracket, E, adjusting-pinion H h k', and jamb-nut G, employed and operating substantially as herein described, the set-screw f f' f'' f'', as and for the purposes set forth.

In testimony of which invention, I hereunto set my hand.

HENRY BARTH.
